UNITED STATES PATENT OFFICE.

FRANCIS P. MCCOLL, OF EASTPORT, MAINE, ASSIGNOR TO AMERICAN KEY CAN COMPANY, OF CHICAGO, ILLINOIS, A CORPORATION OF NEW JERSEY.

ROLL-TOP RECEPTACLE AND METHOD OF MAKING SAME.

1,251,067.

Specification of Letters Patent. Patented Dec. 25, 1917.

Application filed February 1, 1909. Serial No. 475,380.

To all whom it may concern:

Be it known that I, FRANCIS P. McCOLL, a citizen of the United States, residing at Eastport, county of Washington, State of Maine, have invented a certain new and useful Improvement in Roll-Top Receptacles and Methods of Making the Same, and declare the following to be a full, clear, and exact description of the same, such as will enable others skilled in the art to which it pertains to make and use the same, reference being had to the accompanying drawings, which form a part of this specification.

A very convenient and satisfactory can for containing and preserving food commodities is that wherein the cover is soldered to a flange projecting laterally from and surrounding one end of the can body; the cover being provided with a tongue which may be received in a suitable key whereby, upon turning the key, first the tongue and then the cover itself is rolled up on the key so that the cover may be entirely removed. Most food products must be "processed," that is cooked at least partially after they have been placed in the cans and the cans sealed. Heretofore it has been customary to put the cans through the "processing" operation with the roll-top end completed in the form described above. It will be seen that when heat is applied to a sealed, filled can, a fluid pressure is created which tends to move the soldered end of the can bodily in the outward direction. This strain imposed upon the soldered end must be borne by the line of solder nearest the interior of the can and, if the pressure be great enough, the solder will yield and the strain will be transferred to a point a little farther out along the flange. The strain is therefore progressively carried outwardly along the flange as the separation of the cover continues, no aid being given to any portion of the joint by those portions which surround it and the strength of the joint being simply that of an extremely narrow annular ring. Therefore increasing the width of the joint by making the flange upon which the cover is soldered wider does not add proportionately, if at all, to the resisting power of the joint when the cover is subjected to pressure from within. Solder can be made strong enough to withstand "processing" at low temperatures, but the limits of strength of a soldered joint are soon reached and, where high tempera-

tures are needed, as in the case of meats, a very large percentage of roll-top ends of the character described will yield and produce leaks.

The object of my invention is to make it possible to use roll-top cans as receptacles for food commodities which, during "processing" must be subjected to relatively high temperatures.

In accordance with my invention I make the joint between the roll-top and can body in such a manner that resistance to separation while under internal pressure is exerted by the entire joint so that it is not necessary for one portion of the joint to yield before the adjacent portions come into play. I then fill the can or other receptacle, preferably through an open end, seal the opening, subject the package to the "processing" operation and then manipulate the united portions of the body or the receptacle and the cover so as to form them into an annular flange which projects laterally around one end of the body, the final appearance of the package being the same as heretofore.

The various features of novelty whereby my invention is characterized will herein-after be pointed out with particularity in the claims; but, for a full understanding of my invention and of its objects and advantages, reference may be had to the following detailed description taken in connection with the accompanying drawing, wherein: Figure 1 is a section of my improved receptacle ready to be filled; Fig. 2 is a view partly in side elevation and partly in section showing the receptacle filled and sealed; Fig. 3 is a view similar to Fig. 2 showing the completed package after the roll-top end has been given its final shape; Fig. 4 is a bottom plan view of the completed package as shown in Fig. 3; Fig. 5 is a view showing one end of the body of the can or other receptacle before the roll-top end or cover is inserted; and Figs. 6 and 7 are sections showing two different forms of roll-top ends or covers which may be employed.

In the drawing I have illustrated my invention as applied to an ordinary cylindrical, tin can but it will, of course, be understood that the receptacle may be of any other suitable material and have any desired shape.

Referring to the drawing A represents the body of the can and B the cover which

is to form the roll-top. The member B is made cup-shaped so as to have an annular flange C of the desired width projecting laterally from one side thereof. D is a tongue which extends from the free edge of the flange C and forms the means whereby the rolling of the cover upon a key may be begun. The cover is inserted in one end of the body with the flange projecting outwardly, the edge of the flange lying in the plane of the end of the body. The cover is then soldered securely in place in any well known manner as, for example, by carrying the can through a solder bath. The cover is now secured in place by means of a wide band of solder E arranged between the exterior of the flange and the interior of the can body. The can is now filled through its open end F, the filling being easily accomplished by reason of the large opening provided. After the can is filled the open end is closed by means of a cover G, this cover being preferably, though not necessarily, secured by means of a "double seam". The filled can now constitutes a package of the form indicated in Fig. 2. The package is then subjected to the usual "processing" operation and allowed to cool.

It will be seen that, upon the creation of pressure within the package during "processing", the outward thrust upon the member B is borne by the entire joint and it is necessary to shear this joint throughout the entire width of the flange on the cover member before a leak will appear. The difference between this joint and the old form of joint can be clearly seen by comparing Figs. 2 and 3. Assuming that Fig. 3 represents the package which is undergoing "processing" then, the outward pressure upon the member B would simply tend to tear the flange C from the flange H on the can body. The only portion of the joint which could resist the separation of the flanges would be the annular ring e of minute width at the beginning of the joint viewed from the interior of the can. Until this ring gave away no assistance would be rendered to it by the surrounding portions of the joint. As soon as the joint yielded along the line e then the strain would be transferred to another line immediately outside of the former, and this progressive introduction of the different portions of the joint as the active agents would continue until the cover had been entirely torn from the supporting flange on the can body at some point. When the package shown in Fig. 2 is subjected to internal pressure the entire joint consisting of a band extending entirely around the can and having a width from X to Y at once comes into play, each part of the joint supporting the other. By making the distance from X to Y long enough it will become impossible to shear the joint and the only

way in which an opening can be effected will be to cause the metal of the cover to bend and roll around the entire circumference so as to gradually lessen the width of the flange. This could only happen under enormous pressures which would probably disrupt the can or one of the covers at some other point than at the joint under consideration. I prefer to shape the cover so that any pressure which tends to bulge it outwardly does not produce a pull tending to draw the inner portion of the flange away from the can body. This may be accomplished by making the portion of the cover which forms the bottom of the cup concave as viewed from the end of the can after the cover has been inserted, as at I in the form of cover B¹ indicated in Fig. 7 or the central portion K of the bottom may be bulged in the opposite direction as indicated in the remaining figures. In the latter arrangement the portion of the cover immediately adjacent to the flange is in the form of a ring or band k forming an obtuse angle with the flange when viewed from the outside of the can. In either arrangement, however, the main portion of the cover acts as a strut under pressure and forces the flange more tightly against the surrounding wall of the can body instead of tending to tear the flange away.

After the package has passed through the "processing" operation the flange C and the portion of the wall of the can body H to which it is secured are bent outwardly by means of any suitable flanging devices so as to assume the positions shown in Fig. 3. The joint between the roll-top and can body is now at right angles to what it was before and the top or cover may be removed in the usual way by means of a key engaging with the tongue D. It will be seen that after the "processing" operation has been completed and the package has cooled somewhat there is no longer any objection to having the joint occupy the position indicated in Fig. 3 since it is only while the package is under considerable internal pressure that there is danger of disrupting the joint.

In order to make the joint stronger both while undergoing internal compression and afterward, the end of the can body in which the roll-top is secured may be bent backwardly itself as at L thereby forming a reinforcing band throughout the entire width and extent of the joint and making it exceedingly difficult for the extreme end of the can body to become distorted laterally when the cover is subjected to internal pressure.

While I have described in detail only a single form of my invention, namely that which I believe to be the best, I do not desire to be limited except as indicated by the terms employed in the definitions of

my invention constituting the appended claims.

Having now fully described my invention, what I claim as new and desire to secure by Letters Patent is:

6. The method of forming a package having a roll top which consists in filling a receptacle having one end closed by a partially-shaped roll top, closing the open end of the receptacle, heating the receptacle and its contents, and finally completing the shaping of the roll top. 55
7. The method of forming a package having a roll top which consists in filling a receptacle having one end closed by a partially-shaped roll top so shaped as to offer a maximum resistance to rupture between the body of the receptacle and said top under internal pressure, closing the receptacle, heating the receptacle and its contents, and finally completing the shaping of the roll top. 60
8. The method of forming a processed package having a roll top which consists in filling a receptacle having one end closed by means of a head provided with an outwardly-extending flange soldered to the wall of said receptacle, closing said receptacle, heating the receptacle so as to process its contents, and then bending portions of the head and can body laterally. 65
9. The method of making a roll top can which consists in soldering a cup-shaped head in one end of the body with the mouth of the head directed outwardly, closing the other end of the can, processing the can and then bending the united portion of the body and head laterally to form a flange about the body. 70
10. The method of forming a roll end on a can-requiring processing which consists in providing one end of the can with a cup-shaped end soldered into the can, processing the can, and then bending the soldered portion of the can body and of the cup-shaped end laterally and outwardly. 75
5. The method of forming a package having a roll top which consists in filling a receptacle having one end closed by means of a head provided with an outwardly extending flange soldered to the wall of said receptacle, closing said receptacle, and then bending said flange and the adjacent portion of said receptacle laterally. 80
15. The method of forming a package having a roll top which consists in producing a sealed filled receptacle having one end sealed by a partially-shaped roll top so formed as to offer a maximum resistance under internal pressure, heating the receptacle and its contents, and finally completing the shaping of the roll top. 85
20. The method of forming a package having a roll top which consists in producing a sealed filled receptacle having one end sealed by a partially-shaped roll top so formed as to offer a maximum resistance under internal pressure, heating the receptacle and its contents, and finally completing the shaping of the roll top. 90
25. The method of forming a package having a roll top which consists in producing a sealed filled receptacle having one end sealed by a cup-shaped head soldered in place with the mouth of the head directed outwardly, heating the receptacle and its contents, and then bending the united portions of the body and head laterally to form a flange. 95
30. The method of forming a package having a roll top which consists in soldering within one end of an open ended receptacle, a closely-fitting cup-shaped head having the mouth directed outwardly, filling the receptacle, closing the other end of the receptacle, and then bending the united portions of the cup and receptacle laterally to form a flange surrounding the receptacle. 100

In testimony whereof, I sign this specification in the presence of two witnesses.

FRANCIS P. MCCOLL.
